UNITED STATES PATENT OFFICE

HEBER TRIMBLE GEORGE, OF DUNDALK, MARYLAND, ASSIGNOR TO BETHLEHEM STEEL COMPANY, A CORPORATION OF PENNSYLVANIA

ROD COOLING AND WATER ELIMINATING APPARATUS

Application filed April 20, 1929. Serial No. 356,805.

This invention relates to apparatus for cooling metal rods and the removal of the cooling medium from the rods.

Ordinarily the rods as delivered from the rolling mill in a red hot state are passed through a pipe into which water at high pressure is injected to cool the material and the rods then coiled upon reels for further cooling. With the former method, a considerable amount of water is carried to the reels by the rods, where it is evaporated by the remaining heat in the material, and it is found when rolling high carbon rods that the water carried by the rods to the reels causes the hardening of the rods in spots which make it difficult to draw the rods into wire.

The present invention is for the purpose of removing the cooling water from the rods before reaching the reels and for the purpose of further cooling the rods after they have passed through the water cooling pipe.

It contemplates the impingement of water against the rod, in a plane opposite to the direction of travel of the rod, with sufficient force to displace the water carried by the rod as it leaves the cooling pipe on the intake side of the eliminator, thus preventing water being carried to the reels.

It further contemplates an added cooling of the rods after they have passed through the cooling pipe.

The novel features of my invention will be more fully understood from the following description and claims taken with the accompanying drawing, in which:

Fig. 1 illustrates a side elevation of the apparatus with a portion cut away to show the arrangement of parts and principle of my invention; and

Fig. 2 is a cross section taken on line 2—2, and in the direction of the arrows as shown in Fig. 1.

The numeral 10 designates a water tight catch box open at its upper end, to which pipes 11 and 12 are attached and adapted to guide the rod 13 which travels in the direction of the arrow. A bottom opening is provided through which the water is drained into the pipe 14.

The eliminator comprises a rectangular sectioned supporting member 15 having a depending leg 16 at each end. The legs are bored and threaded to receive the pipes 11 and 12.

Between the leg portions, a series of guides 17 are attached to the longitudinal piece 15, for the purpose of directing the end of the rod as it passes from the pipe 11 to pipe 12. The ends of the guides 17 and the depending legs 16 are counter-bored to provide enlarged openings 18 adapted to receive the end of the rod as it passes through the box. Each guide is provided with a stud 19 which is adapted to project through a hole in the support 15. The ends of the studs are slotted through which keys 20 are driven to secure the guides to the support.

Above the support 15 is positioned a closed end manifold 21 having downwardly projecting nipples 22 communicating with the manifold. The ends of the nipples are adapted to fit into openings 23 which extend through the support 15. It will be noted that the nipples and their respective openings in the member 15 are inclined at an angle in the direction of the incoming pipe 11. The discharge orifices 24 at the under side of the support are adapted to produce sharp and high velocity streams to counter-act against the water clinging to the rod as it passes between the guides.

Suitable means are provided for securing the supporting member 15, the manifold 21 and the various pipes to the catch box.

In operation, the hot rod as it comes from the mill, is directed into the end of the cooling pipe 11 which is supplied with high pressure water. During its passage through the pipe, the rod is in intimate contact with the cooling water.

As the rod enters the catch box, its end is directed across the box to the outlet pipe 12 by means of the spaced guides 17 from whence it passes on to the reels.

Inasmuch that the rod is surrounded by water as it comes from the cooling pipe, a considerable portion of the water is carried along by the rod as it passes through the box on its way to the reels. To remove this water from the rod, water under high pressure is

angularly directed against the rod through the orifices 24, which is supplied by means of the manifold and the nipples connecting the manifold and the openings in the supporting member 15. The effect of the transversely directed jets of high pressure water causes the flow of water following the rod to be cut abruptly in a plane substantially opposite to its line of travel, and as the velocity of the impinging water is greater than the velocity of the moving rod and the water clinging thereto, a portion of the water on the rod is picked up by each impinging jet and thrown off the rod into the catch box. The amount of water following the rod becomes less and less between each successive jet and when the last jet at the delivery end of the box is reached, only a thin film clings to the rod which is finally swept off. The velocity of the last impinging jet of water is sufficient to leave very little moisture on the rod which is evaporated by the time the rod reaches the reels, thereby assuring the uniform cooling and condition of the rod.

25 The amount of water from the jets adhering to the rod is inconsequential, due to the high velocity of the jet and the small projected surface of the rod in the path of the jet.

30 Directing the high pressure jets of water at an angle inclined in the direction of the pipe 11, aids materially in cutting the water following the rod as it passes through the box, and the water thus picked up by each jet is swept from the rod in a direction opposed to the direction of travel of the rod.

It will be seen from the foregoing description that I have devised a means for cooling rods by the use of water surrounding the rod, and that I have provided means for further cooling the rod by means of high pressure impinging jets of water directed against one side of the rod and to effect the elimination of the first said cooling water from the rod.

45 While I have shown my invention in but one form it will be obvious to those skilled in the art that it is not so limited, but is susceptible of various other changes and modifications without departing from the spirit thereof, and I desire therefore that only such limitations shall be placed thereupon as are imposed by the prior art, or as are specifically set forth in the appended claims.

Having thus described my invention what I claim as new and desired to secure by Letters Patent is:

50 1. In an apparatus for cooling a metal rod; a catch box, inlet and outlet pipes for said rod connected to said box, means within said box adapted to guide said rod, means for directing cooling water against said rod, and a water outlet for the box.

55 2. In an apparatus for cooling a metal rod; a catch box, a water cooling pipe for the passage of said rod, an outlet pipe for said rod,

means intermediate the ends of said pipes adapted to guide said rod, means within said box for directing cooling water against said rod, and a water outlet for the box.

3. In an apparatus for cooling a metal rod; 70 a catch box, a water cooling pipe for the passage of said rod at one end of the box, an outlet pipe for said rod at the other end of the box, spaced guides intermediate the ends of said pipes adapted to guide said rod, means 75 between said guides for directing cooling water transversely against said rod, and a water outlet for the box.

4. In an apparatus for cooling a metal rod; 80 a catch box, a water cooling pipe for the passage of said rod, an outlet pipe for said rod, means at the ends of the box adapted to receive the ends of said pipes and to guide said rod, spaced guides intermediate said end guides and aligned therewith, means between 85 said guides for directing single jets of water transversely against said rod, and a water outlet for the box.

5. In an apparatus for cooling a metal rod; 90 a catch box, a water cooling pipe for the passage of said rod connected to one end of the box, an outlet pipe for said rod connected to the opposite end of the box, spaced guiding means intermediate the ends of said pipes adapted to guide said rod from said cooling 95 pipe to said rod outlet pipe, means for directing jets of water between said guiding means against one side of said rod, and a water outlet for the box.

6. In an apparatus for cooling a metal rod; 100 a catch box having a drain, a water inlet pipe for the passage of said rod connected to one end of the box, an outlet pipe for said rod connected to the opposite end of the box, spaced guiding means intermediate the ends 105 of said pipes adapted to to guide said rod from said inlet pipe to said outlet pipe, and means adapted to direct jets of water into the box in a plane crossing the longitudinal axis of said inlet and outlet pipes, whereby the 110 water following said rod as it enters the box from said inlet pipe will be dissipated into the box.

7. In an apparatus for cooling a metal rod; 115 a catch box having a drain, a water inlet pipe for the passage of said rod, an outlet pipe for said rod, means at the ends of the box adapted to receive the ends of said pipes and to guide said rod, spaced guides intermediate said end guides and aligned therewith, a support for 120 said guides, and means for directing jets of water between said guides against one side of said rod, said guides being adapted to be removably attached to said support.

8. In an apparatus for cooling a metal rod; 125 a water tight box having an open top and a drain at its bottom, a water inlet pipe for the passage of said rod, an outlet pipe for said rod, spaced guides intermediate the ends of said pipes adapted to guide said rod, a sup- 130

port for said guides having spaced openings therethrough, a water conductor in spaced relation to said support, and communicating means between said conductor and the openings in said support, whereby water may be directed into the box in a plane crossing the longitudinal axis of said inlet and outlet pipes.

9. In an apparatus for cooling a metal rod; 10 a water tight box having an open top and a drain at its bottom, a water inlet pipe for the passage of said rod, an outlet pipe for said rod, spaced guides intermediate the ends of said pipes adapted to guide said rod, a support for said guides having spaced openings therethrough, a water conductor in spaced relation to said support, and communicating means between said conductor and the openings in said support, said openings being 20 adapted to produce sharp jets of water directed in a plane crossing the longitudinal axis of said inlet and outlet pipes.

10. In apparatus of the class described, the combination with means for water-cooling a rapidly moving hot metal rod, of means for impinging jets of fluid against the rod at an angle to the direction of movement thereof, to divert from the surface of the rod the cooling water that is carried thereby, and 25 means for guiding the rod in a substantially straight path during the impinging of said jets of fluid against the same.

11. In apparatus of the class described, the combination with means for water-cooling a rapidly moving hot metal rod, of means for impinging jets of fluid against the rod at an angle to the direction of movement thereof, to divert from the surface of the rod the cooling water that is carried thereby, and 30 means for guiding the rod in a substantially straight path during the impinging of said jets of fluid against the same.

12. In apparatus of the class described, the combination with means for water-cooling a rapidly moving hot metal rod, of means for impinging jets of fluid against the rod at an angle to the direction of movement thereof, to divert from the surface of the rod the cooling water that is carried thereby.

In testimony whereof I hereunto affix my signature.

HEBER TRIMBLE GEORGE.
